UNITED STATES PATENT OFFICE.

JOHN I. McKEAN, OF PARKERSBURG, WEST VIRGINIA, ASSIGNEE TO STANDARD OIL DEVELOPMENT COMPANY, A CORPORATION OF DELAWARE.

TUG WHEEL.

Application filed April 13, 1923. Serial No. 631,765.

This invention relates to well drilling equipment and will be fully understood from the following description, taken in connection with the accompanying drawing, in which—

Fig. 1 is a side elevation of a tug wheel embodying the invention;

Fig. 2 is an edge view of the same, looking in the direction of the arrow II on Fig. 1; and

Fig. 3 is a similar view, looking in the direction of the arrow III on Fig. 1.

In an old construction of tug wheel, rope-engaging cleats were placed out on one or more spokes of the wheel. These in use carried too much uneven stress onto the spokes involved and caused racking of the wheel.

A problem is presented in a device of this character to construct rope-engaging members which will be suitably attached to the wheel, but yet not be a source of weakening.

Referring to the drawing illustrative of the present invention, the reference character 1 designates a shaft, for example a bull-wheel shaft, parts not essential to an understanding of the invention being broken away, and secured on the shaft is a tug wheel 2. Fastened to the shaft and to the wheel by suitable fastening means as desired is a member A the end 3 of which is positioned as a buttress against a member B which is similarly fastened to the shaft and wheel. The end 4 of the member B is positioned as a buttress against a member C and the end 5 of the member C is in turn positioned as a buttress against a member D also similarly fastened to the shaft and wheel. Extending out from the member D either as an attached extension or as an integral prolongation is a rope-engaging projection 8 which is fastened to the rim and preferably set in. The members A, B, C and D fastened to the shaft, on suitable facets, and fastened together in successive series are in effect a braced framing secured to the shaft, and the free ends 6, 7 etc., presents rope-engaging projection, thus constituting the members B, C, and D rope-engaging members. As seen, the end 8 extends beyond the rim, the end 7 is nearer the center of the wheel and

the end 6 still nearer, the series forming progressive steps for engaging the rope. Tie-strips 9 align the members A, B, C and D with the spokes respectively adjacent them.

The manner of use of the device will be clear to those skilled in the art, it being understood that the grooved rim of the wheel receives the driving rope or belt which transmits the power to turn the bull-wheel shaft to pull out the tool-string, and so on, and the rope-engaging members on the side of the wheel enable easy and safe throwing of the driving rope or "bull-rope" in making changes.

What I claim is:

1. In combination, a shaft, a rope-operated tug rim, spokes fitted to shaft and rim, and a series of rope-engaging members at one side of the wheel and arranged to receive the rope when displaced from the wheel, said members being fastened to the shaft and braced against each other in succession, one of the rope-engaging members being set into the side of the rim of the wheel.

2. In combination, a shaft, a rope-operated tug rim, spokes securing rim to said shaft, and a series of rope-engaging members at the side of the wheel and arranged to receive the rope when displaced from the wheel, said members being fastened to the shaft and braced against each other in succession.

3. In combination, a shaft, a rope-operated tug rim, spokes securing rim to shaft, and a series of rope-engaging members at the side of the wheel and arranged to receive the rope when displaced from the wheel, said members being braced against each other in succession and having their rope-engaging ends positioned at progressive distances from the center of the wheel.

4. In combination, a shaft, a rope-operated tug rim, spokes secured to shaft and rim, and a series of rope-engaging members at the side of the wheel and arranged to receive the rope when displaced from the wheel, said members being braced against each other in succession.

JOHN I. McKEAN.
